UNITED STATES PATENT OFFICE.

JOHN CHARLES DOWNEY, OF WATERBURY, CONNECTICUT, ASSIGNOR OF TWO-THIRDS TO JOHN P. GRIMES AND EDWARD H. DEELY, OF WATERBURY, CONNECTICUT.

CLASP FOR GARMENT-SUPPORTERS.

SPECIFICATION forming part of Letters Patent No. 772,875, dated October 18, 1904.

Application filed February 1, 1904. Serial No. 191,503. (No model.)

To all whom it may concern:

Be it known that I, JOHN CHARLES DOWNEY, a citizen of the United States, and a resident of Waterbury, in the county of New Haven and State of Connecticut, have invented a new and Improved Clasp for Garment-Supporters, of which the following is a full, clear, and exact description.

The object of this invention is to provide novel details of construction for a clasp that adapt it for very effective service as a means for detachably connecting the leg of a stocking with an elastic band used as a stocking-supporter, but which may also be used in connection with other garment-supporters.

The invention consists in the novel construction and combination of parts as is hereinafter described, and defined in the appended claims.

Reference is to be had to the accompanying drawings, forming a part of this specification, in which similar characters of reference indicate corresponding parts in all the figures.

Figure 1 is a front view of the improved clasp pendent from the looped lower end of a garter-band. Fig. 2 is a longitudinal sectional view of the improved clasp, taken substantially on the line 2 2 in Fig. 1 and showing a portion of a stocking gripped by the clasp. Fig. 3 is a view similar to Fig. 2, showing the details of the clasp adjusted for the reception of the fabric to be held thereby, and Fig. 4 is a transverse sectional view substantially on the line 4 4 in Fig. 1.

The body of the clasp is in the form of an elongated frame that may with advantage be constructed of a wire rod bent into shape, thus providing two side bars 5 5, that are integral with and spaced apart in parallel planes by a top cross-bar 5^a and a bottom cross-bar 5^b, as shown in Fig. 1. Upon the side bars 5, that afford effective guides, a grip-jaw 6 is mounted to slide, said grip-jaw comprising a plate-metal body portion furnished with a series of teeth *a* on the straight lower edge thereof and also provided with two opposite tubular boxes *b*, which are loosely mounted upon the respective guides 5, whereby the

jaw is adapted to reciprocate on the guides toward and from the lower cross-bar 5^b.

An arm 7, formed of plate metal, is hinged upon the upper part of the grip-jaw 6, preferably as shown, the jointed connection consisting of a transverse tubulation *c*, formed on the lower end of the arm and loosely coupled with a cross-bar *c'*, formed integral with the grip-jaw by slotting the latter transversely near the upper edge of the same, as shown at *c'* in Fig. 1. A suitable length is given to the arm 7 and near its upper end it is provided with the similar stops *d*, that are slightly curved projections from the side edges of the arm and seat loosely upon the guides 5, as shown in Figs. 1 and 4.

Between the stops *d* a transverse slot *e* is formed in the upper portion of the arm 7 at a proper distance from the upper edge thereof, thus affording a cross-bar *e*, defined by the slot and said edge.

A link-plate 8, consisting of a sheet-metal strip provided with transverse tubulations *g* *h*, formed thereon, respectively at the lower and upper ends, is jointed upon the cross-bar *e* and upper cross-bar 5^a of the clasp-frame by the loose engagement of said tubulations 75 respectively therewith.

A head-link 9 is provided for the connection of the clasp with an end portion *A* of a garter, the latter, which is shown doubled, being the pendent part of an elastic band such as is usually employed for engagement with the lower limb of the wearer by encircling the same, and as this is a common provision the main portion of the garter-band is omitted from the drawings.

The head-link 9 is formed of plate metal transversely slotted at *i* near its upper transverse edge, said slot having sufficient length and width to adapt it to freely receive the garter-band *A*, that is doubled to produce a loop that engages with the transverse bar *m*, produced by the formation of the slot *i*. Below the slot *i* the material is centrally notched in rectangular form, as shown at *n* in Fig. 1, the notch affording proper clearance for the upper end of the link-plate 8, and at each side

of said notch short clip-bands *o* are formed by bending the material into tubular form, these clip-bands being mounted and secured upon the upper ends of the guides *5* near 5 their junction with the top cross-bar *5^a*.

It will be seen that the clasp is hung 10 pendant from the garter-band, that in complete form may be secured upon the leg of the wearer near the knee, so that the upper edge 15 portion of a stocking *B* may be engaged with the clasp and thus adapt the garter for the support of the stocking, as usual.

To connect the stocking with the clasp, the arm *7* is moved upward and rocked outward 15 at its upper end, which will slide the grip-jaw *6* upward and away from the lower cross-bar *5^b* and project the link-plate *8* outward correspondingly; as represented in Fig. 3. The 20 fibrous material that forms the edge portion 25 of the stocking is now doubled and pushed through the clasp-frame between the serrated lower edge of the grip-jaw *6* and the upper surface of the lower cross-bar *5^b*, and the link-plate *8* and arm *7* are pressed at their joint *c c'* toward the frame of the clasp, which will depress the grip-jaw and clasp the stocking between the teeth *a* and the cross-bar *5^b*.

It will be seen that the relative adjustment 30 of the arm *7* and link-plate *8* prevents an accidental release of the stocking from the clasp when engaged therewith, as indicated in Fig. 2, but that upon applying slight pressure at the joint *c*, upon the normal rear side of the 35 same, the joint may be readily flexed and the stocking be released in an obvious manner.

Having thus described my invention, I claim as new and desire to secure by Letters Patent—

1. A clasp comprising a frame, a gripping 40 member slideable on the frame, a rock-arm hinged upon the gripping member, a link loosely connecting the rock-arm with the frame, and means for connecting the frame with a supporting member.

45 2. A clasp, comprising a quadrangular frame, a grip-jaw held to slide on the frame near the lower cross-bar thereof, a rock-arm hinged upon the grip-jaw, a link loosely connecting the rock-arm with the upper cross-

bar of the frame, and means for connecting 50 the upper portion of the frame with a garter-band.

3. A clasp, comprising a quadrangular frame, that affords parallel guides as side members thereof, a grip-jaw having a serrated 55 lower edge that is opposed to the lower cross-bar on the frame, and two lateral tubular formations thereon which loosely engage the guides, a rock-arm hinged at its lower end on the upper portion of the grip-jaw and having 60 laterally-extended stops near the upper end, which normally seat upon the guides, a link-plate hinged at its respective ends upon the upper end of the rock-arm and the upper cross-bar of the frame, and means for connecting 65 the upper portion of the frame with a looped end of a garter-band.

4. The combination with a looped end of a garter-band, of a stocking - gripping clasp, comprising a quadrangular frame formed of a 70 wire rod bent into shape, affording two parallel guides, a lower cross-bar and an upper cross-bar, a plate-metal grip-jaw, formed with teeth on the lower transverse edge, said jaw having two opposite tubular formations formed on 75 its side edges and which loosely engage the guides, said jaw having a cross-bar at the upper transverse edge, produced by slotting the jaw near said edge, a rock-arm formed of plate metal and hinged at its lower end upon the 80 cross-bar, said rock-arm having laterally-extended stops thereon near its upper end, which normally seat upon the guides, a link-plate hinged at its ends respectively upon the upper end of the rock-arm and upon the upper 85 cross-bar of the frame, and a head-link secured upon the upper portion of the frame and having a transverse slot near its upper edge, providing a cross-bar that is engaged by the doubled end portion of the garter-band. 90

In testimony whereof I have signed my name to this specification in the presence of two subscribing witnesses.

JOHN CHARLES DOWNEY.
